(57) **CLAIM**

The ornamental design for a coffee table, as shown and described.

DESCRIPTION

FIG. 1 is a top, front and left side perspective view of a first embodiment of a coffee table, showing my new design; FIG. 2 is a bottom, front and right side perspective view thereof;

FIG. 3 is front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is a top perspective view of a second embodiment of the coffee table;

FIG. 12 is a bottom perspective view of FIG. 11;

FIG. 13 is a front elevational view of FIG. 11;

FIG. 14 is a rear elevational view of FIG. 11;

FIG. 15 is a left side elevational view of FIG. 11;

FIG. 16 is a right side elevational view of FIG. 11;

FIG. 17 is a top plan view of FIG. 11;

FIG. 18 is a bottom plan view of FIG. 11; and,

FIG. 19 is an enlarged view of portion 19 in FIG. 11.

The broken lines show the features of the coffee table that form no part of the claimed design. The dash-dot-dash broken lines define the boundary of enlarged views and form no part of the claimed design.

1 Claim, 19 Drawing Sheets
